UNITED STATES PATENT OFFICE.

WILLIAM HEFFNER, OF MINNEAPOLIS, MINNESOTA.

DESIGN FOR A FIRE-CRACKER HOLDER.

SPECIFICATION forming part of Design No. 31,454, dated August 22, 1899.

Application filed December 10, 1897. Serial No. 661,465. Term of patent 7 years.

To all whom it may concern:

Be it known that I, WILLIAM HEFFNER, a citizen of the United States, residing at Minneapolis, Hennepin county, Minnesota, have ⁵ invented and produced a new and original Design for Fire-Cracker Holders, of which the following is a specification, reference being had therein to the accompanying drawings, forming a part thereof, and in which—

- 10 Figure 1 is a perspective view of the article. Fig. 2 is a central longitudinal section thereof. As shown in the said drawings, the leading feature of my design consists in a collar at one end, a truncated cone at the other end, ¹⁵ and arms connecting one extremity of the collar with the smaller extremity of the cone, the latter having a tapered cavity for the reception of the fire-cracker or other like pyrotechnic article.

20 Referring by reference-letters to the draw-

ings, C is a collar cylindrical exteriorly and interiorly. T is a truncated cone having a tapered cavity or socket S within and through its body and its axis parallel with that of the collar, and A A are arms connecting the inner extremity of the collar with the inner and smaller extremity of the cone. ²⁵

Having thus described my invention, what I claim as new, and desire to secure by Letters Patent, is—

The design for a fire-cracker holder, substantially as herein shown and described.

In testimony whereof I have hereunto set my hand in presence of two subscribing witnesses.

WILLIAM HEFFNER.
